DESIGN FOR A GARTER CLASP LOOP

Robert Tilly, New York, N. Y.

Application March 8, 1934, Serial No. 50,982

Term of patent 14 years

To all whom it may concern:

Be it known that I, ROBERT TILLY, a citizen of the United States and resident of New York, in the county of New York and State of New York, have invented a new, original, and ornamental Design for a Garter Clasp Loop, of which the following is a specification, reference being had to the accompanying drawing, forming part thereof.

In the drawing:

Fig. 1 is a front view of a garter clasp loop showing my new design.

Fig. 2 is a side edge view thereof.

Fig. 3 is a cross sectional view taken approximately on the line 3—3 of Fig. 1.

I claim:

The ornamental design for a garter clasp loop substantially as shown.

ROBERT TILLY.
